FREQUENCY MODULATION DISCRIMINA-
TOR CIRCUITMurray G. Crosby, Riverhead, N. Y., assignor to
Radio Corporation of America, a corporation
of Delaware

Application April 29, 1943, Serial No. 484,973

9 Claims. (Cl. 250—27)

My present invention relates generally to frequency discriminator circuits, and more particularly to novel forms of discriminator circuits for frequency modulated (FM) carrier wave energy.

An object of my invention is to provide an FM detector circuit wherein a pair of opposed rectifiers is fed by a discriminator which consists of a resonant circuit path for feeding both rectifiers in parallel with retarded FM signal energy, and additional paths for feeding the rectifiers with unretarded FM signal energy, but in opposite polarity.

Another object of my invention is to provide a discriminator for FM signal energy wherein there is provided a parallel resonant circuit path functioning to feed retarded FM signal energy to a detector for frequencies off the predetermined frequency of the parallel resonant circuit, there being provided a second path to the detector circuit for feeding to the latter unretarded FM signal energy.

The novel features which I believe to be characteristic of my invention are set forth with particularity in the appended claims; the invention itself, however, as to both its organization and method of operation will best be understood by reference to the following description, taken in connection with the drawings, in which I have indicated diagrammatically several circuit organizations whereby my invention may be carried into effect.

In the drawings:

Fig. 1 shows one form of a discriminator-rectifier circuit embodying the invention.

Fig. 1a shows a modification of the circuit arrangement of Fig. 1.

Figs. 2a and 2b show graphically the vector relations between the retarded and unretarded signal energies of Figs. 1 and 1a for the "in-tune" condition as well as for the "off-tune" condition.

Fig. 3 shows a modified form of the invention.

Fig. 3a shows the frequency-amplitude characteristic of the parallel resonant circuit of the discriminator in Fig. 3.

Fig. 3b vectorially illustrates the "off-tune" condition of the discriminator in Fig. 3.

Fig. 4 shows a circuit embodying a modification of the discriminator of Fig. 3.

Referring now to the accompanying drawings, wherein like reference characters in the different figures designate similar elements, in Fig. 1 the opposed rectifiers 1 and 2, specifically disclosed as of the diode type, function as a means for rectifying signal energy applied thereto. The

source of the signal energy is not disclosed, because it may be of any well known form. For example, where the invention is used in a superheterodyne receiver of FM signal energy it will be clear that the transformer 3 may be an intermediate frequency (I. F.) transformer which is fed from the plate circuit of a prior stage of I. F. amplification, or from the plate circuit of an amplitude limiter tube. In any event the primary circuit 4 of transformer 3 is fixedly tuned to the operating I. F. value of the receiver. The FM signal energy itself may either have a high or low deviation range. Again, the FM signal energy received at the signal collector device of the receiver may be in the megacycle (Mc.) range, and the I. F. value itself may be in the megacycle or kilocycle bands.

The secondary winding 7 of transformer 3 has its upper end connected to the anodes of rectifiers 1 and 2 through a path which includes the series resonant circuit S. This series resonant circuit S is tuned to the mean, or center, frequency of the applied FM signal energy. This frequency will, of course, be the frequency to which the primary and secondary circuits of transformer 3 are tuned. The series resonant circuit specifically consists of condenser 8 and inductance 9. The output terminal of the series resonant circuit S is connected to the respective anodes of diodes 1 and 2 through resistors 10 and 11 respectively. The opposite ends of winding 7 are respectively connected to the anodes of rectifiers 1 and 2 through non-selective paths consisting of respective condensers 5 and 6. The condenser 5 shunts the series resonant circuit S and resistor 10. The condenser 6 is connected directly from the lower end of winding 7 to the anode of rectifier 2. The midpoint of winding 7 is effectively grounded for radio frequencies by virtue of its connection to ground through a path which includes the load resistor 12.

This load resistor 12 is arranged in series with load resistor 13, and the cathode end of resistor 12 is grounded. Each of resistors 13 and 12 is shunted by a respective carrier frequency bypass condenser. Resistor 14 is a direct current return resistor connected between the anode of rectifier 1 and the junction of resistors 13 and 12. Resistor 15 functions as a direct current return resistor, and is connected between the anode of rectifier 2 and the aforementioned junction point. It will be understood that from the cathode end of resistor 13 there is derived the differential resultant of the rectified output voltage of each of rectifiers 1 and 2. This differ-

tial resultant voltage may be the modulation signal voltage, such as audio frequency voltage, which is utilized in subsequent audio frequency amplifiers. There may, also, be taken off from the cathode end of resistor 13 automatic frequency control (AFC) voltage for correcting the frequency of the local oscillator of the superheterodyne receiver so as to compensate for any relatively slow shifts in the mean frequency of the FM signal energy applied to the input transformer 3.

Considering the functioning of the network of Fig. 1 it is pointed out that for the "in-tune" condition, depicted in Fig. 2a, the voltage which is fed to each of the rectifiers through the series resonant path S may be represented by the vector E_s . In the in-tune condition of the applied signal energy the mean frequency of such applied energy is, of course, equal to the resonant frequency of series resonant circuit S. The circuit S, as is well known, retards or shifts the phase of the signal voltage applied thereto to an increasing degree for frequencies departing from the mean or carrier frequency value. Hence, there will be no phase shift of the signal voltage applied to S at the instant when its mean frequency is equal to that of circuit S. Since the resonant circuit S feeds the rectifiers through resistive elements 10 and 11, it follows that at the instant when the applied signal energy is at the mean frequency there will be no phase shift provided in the signal energy developed at the output terminal of S which is fed in like polarity to the rectifiers. This would also be true at other instantaneous frequencies of the signal energy.

However, the signal voltage fed through condensers 5 and 6 is derived from the opposite ends of winding 7. Since the midpoint of winding 7 is effectively grounded for radio frequency energy, it follows that the voltages fed through condensers 5 and 6 are respectively of different polarity. Furthermore, these voltages have a phase shift of 90 degrees with respect to the retarded voltage fed through the series resonant circuit S. The condensers 5 and 6 do not have the selective phase shift characteristic of circuit S. They affect the signal energy in a non-selective manner at all instantaneous frequencies. Fig. 2a shows the vector representations of the voltages E_6 and E_5 which are fed through condensers 6 and 5 respectively. It will, therefore, be seen that there is applied to each of rectifiers 1 and 2 a resultant voltage which is vectorially represented by a dashed arrow. These resultant vectors are of equal magnitude for the in-tune condition. Hence, the rectified voltages developed across resistors 13 and 12 are equal, and accordingly, the differential voltage taken off from the cathode end of resistor 13 is zero.

However, for the "off-tune" condition, there is a different state of affairs which is depicted in Fig. 2b. At the instant the frequency of the applied signal energy is different from the resonant frequency of series resonant circuit S, there is produced a phase shift in the voltage fed therethrough. As previously explained this phase shift is increasingly greater in proportion to the departure of the instantaneous signal frequency from the mean frequency thereof. The vector E_s in Fig. 2b represents the voltage now fed through the series resonant circuit, and it will be seen that some phase shift has been provided in this vector relative to the angular position of

5 E₅ in Fig. 2a. The signal voltage which passes through condensers 5 and 6 respectively has not been affected either in magnitude or phase with respect to the condition therein in the "in-tune" state depicted in Fig. 2a. That is, each of condensers 5 and 6 has the same effect on the signal voltage passed therethrough for the in-tune and off-tune states. Hence, the resultant vectors applied to the respective rectifiers 1 and 2 are now substantially as represented in Fig. 2b. One of these resultant vectors exceeds the other in magnitude, and the differential voltage derived from the cathode end of resistor 13 has some value. The value of the differential voltage is dependent upon the magnitude of frequency difference between the instantaneous frequency of the applied signal energy and the predetermined frequency of series resonant circuit S. In the case where there occurs a relatively slow departure of the signal energy mean frequency from the aforesaid predetermined frequency of circuit S, the differential voltage is used for AFC voltage. The relatively fast frequency deviations of the signal energy from said predetermined frequency show up as modulation variations of said differential voltage.

20 In Fig. 1a there is shown a modification wherein in the series resonant circuit 8-9 is fed from a single resonant circuit 3' located in the plate circuit of the prior amplifier tube 4'. The coil of tuned circuit 3' is center-tapped by the +B voltage line which feeds the plate of tube 4'. The +B line is bypassed to ground for signal frequencies, and therefore the center tap is at ground potential for signal frequencies. In this way there is provided the opposite polarity voltages for the paths 5 and 6. The circuit is otherwise similar in action to that of Fig. 1. The advantage of this circuit is that the two circuits 4 and 7 of Fig. 1 have been replaced by a single input circuit.

25 It is not necessary to employ a series resonant circuit in the retarding or common selective phase shift path to the opposed rectifiers. In Fig. 3 I have shown a parallel resonant circuit T which specifically consists of an inductance 9' and a shunt condenser 8'. The parallel resonant circuit T is tuned, as was the series resonant circuit S, to the desired or predetermined mean frequency of applied signal energy. That is, the 30 circuit T is tuned to the same frequency as the input transformer 3. In the case of a superheterodyne receiver the transformer circuits and T will be tuned to the operating I. F. value. There is a difference in operation in this modification by virtue of the nature of the frequency-amplitude characteristic of circuit T.

35 Referring to the purely qualitative representation of Fig. 3a it will be seen that at the predetermined resonant frequency F_c of the circuit 40 T, the voltage transmitted through the parallel resonant circuit T is zero. For frequencies less than, or greater than, the resonant frequency of circuit T, the amplitude of the transmitted current increases in magnitude in a positive or negative sense respectively. The positive increase in current is inductive in nature, whereas the negative increase in current is capacitive in nature. Those skilled in the art are fully aware of this 45 fact.

50 50 Reference is now made to Fig. 3b which pictorially represents the vector relations which exist for the off-tune condition of the circuit of Fig. 3. The vectors E_6 and E_5 are similar to those 55 shown in Fig. 2b. That is, the FM signal energy

transmitted through condensers 5 and 6 are shifted 90 degrees in phase, and are applied to the rectifiers 1 and 2 in opposite polarity. At the in-tune condition, that is when the mean frequency of the applied signal energy is exactly equal to the frequency F_c of tuned circuit T, the vector E_t representing the voltage transmitted through circuit T is zero. Therefore, there will be applied to the opposed rectifiers 1 and 2 voltages E_5 and E_6 respectively, and the differential output voltage will be zero. However, for the off-tune condition the vector E_t will have a length which depends on the frequency difference between the instantaneous frequency of the applied signal energy and the frequency F_c . The vector E_t will be in aiding phase with either of vectors E_5 or E_6 depending upon the direction in which the instantaneous frequency of applied signal energy differs from F_c . This follows from the amplitude-frequency characteristic of Fig. 3a. The signal current through circuit T will be in phase with the current through condenser 5 or condenser 6 depending upon the direction of frequency deviation of the signal energy relative to F_c . Accordingly, the vector E_t will be added on either of vectors E_5 or E_6 , and in this way one of the rectifiers will have signal voltage of larger magnitude applied thereto than the other rectifier. It will, therefore, be noted that for the arrangement shown in Fig. 1 the resultant vectors are produced by virtue of an angular difference between the retarded and unretarded voltages, whereas for the arrangement shown in Fig. 3 the resultant vectors arise by virtue of a simple additive, or aiding, phase relation between one of the unretarded voltages E_6 or E_5 and the retarded voltage E_t .

In Fig. 4 I have shown a further modification which is essentially based on the arrangement shown in Fig. 3. In the case of Fig. 4 the 90 degree phase shift effected by the tuned transformer 3 is utilized to properly phase the combination of voltages fed to each diode. The transformer is tuned for band pass action, and may be properly damped by primary and secondary resistors 20 and 21, as shown, or the damping may consist of the losses in the primary and secondary coils. The midpoint of winding 7 is connected to the junction of the load resistors 13 and 12 through a parallel resonant circuit T'. The midpoint of winding 7 is additionally connected to the high potential side of resonant circuit 4 through a path consisting of blocking condenser 5 in series with the parallel resonant circuit T. The opposite side of resonant circuit 4 is connected to the midpoint of winding 7 through a path which consists of blocking condenser 6 in series with an adjustable resistor R. The midpoint of the primary winding of transformer 3 is connected to the +B line of the direct current voltage supply source for the plate of the immediately preceding amplifier tube. Here, again, the +B line is bypassed to ground for signal frequencies.

In Fig. 4 the voltages E_5 and E_6 are fed to diodes 1 and 2 through mid-tapped winding 7. E_t is fed through T which has its resistance balanced out by R at the resonant frequency F_c . This balance causes voltage feed through T and R to have the amplitude-frequency characteristic of Fig. 3a. The circuit T' serves as an output impedance across which voltage of T and R appears. The high side of T' is connected to the mid-tap of 7 so that the voltage across T' is fed in phase to the opposed diodes, and combines

with voltages induced in 7 in the manner of Fig. 3b.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a system of the type comprising a pair of opposed rectifiers having a differential output circuit, a discriminator circuit feeding the opposed rectifiers, a source of frequency-variable signal energy coupled to said discriminator, the improvement in the discriminator comprising a signal energy retarding path consisting of a series resonant circuit tuned to the mean frequency of applied signal energy, aperiodic means connecting said series resonant circuit in parallel to said rectifiers, and a pair of non-retarding paths connecting said source to respective rectifiers thereby to apply retarded signal voltage to said rectifiers in opposite polarity.
2. In combination with a source of frequency-variable signal energy and a pair of opposed rectifiers having a differential output circuit, a discriminator circuit comprising a retarding path consisting of a parallel resonant circuit tuned to the mean frequency of applied frequency-variable signal energy, means for applying the output of said parallel resonant circuit in parallel to said rectifiers, a second path feeding the signal energy to one of the rectifiers with a relative phase shift of 90 degrees, and a third path feeding the signal energy to the second rectifier in opposite polarity to the signal energy fed through the second path but with a similar quadrature phase shift.
3. In a system of the type comprising a pair of opposed rectifiers having a differential output circuit, a discriminator circuit feeding the opposed rectifiers, a source of frequency-variable signal energy coupled to said discriminator, the improvement in the discriminator comprising a signal energy retarding path consisting of a series resonant circuit tuned to the mean frequency of applied signal energy, aperiodic means connecting said series resonant circuit in parallel to said rectifiers, and a pair of non-retarding paths connecting said source to respective rectifiers thereby to apply retarded signal voltage to said rectifiers in opposite polarity, and said aperiodic means functioning to isolate said retarding path from the non-retarding paths.
4. In combination with a source of frequency-variable signal energy and a pair of opposed rectifiers having a differential output circuit, a discriminator circuit comprising a retarding path consisting of a parallel resonant circuit tuned to the mean frequency of applied frequency-variable signal energy, means for applying the output of said parallel resonant circuit in parallel to said rectifiers, a second path feeding the signal energy to one of the rectifiers with a relative phase shift of 90 degrees, and a third path feeding the signal energy to the second rectifier in opposite polarity to the signal energy fed through the second path but with a similar quadrature phase shift, and isolation resistors being inserted between said parallel resonant circuit and each of said second and third paths.
5. In a frequency discriminator network including a pair of opposed rectifiers, a signal retarding path consisting of a tuned circuit com-

posed of separate reactances of opposite sign, means for applying retarded signal voltage to the rectifiers in like polarity, separate non-selective paths for feeding unretarded signal voltages to the rectifiers in opposite polarity, and said applying means being constructed and arranged to isolate the signal retarding path from the separate paths.

6. In a frequency modulation detector, a pair of opposed rectifiers, a discriminator circuit for the rectifiers comprising a resonant circuit signal retard path, isolation resistors connecting said resonant circuit in parallel to the rectifiers, and non-selective means for feeding the latter with unretarded signal voltages of opposite polarity.

7. In a system of the type comprising a pair of opposed rectifiers having a differential output circuit, a discriminator circuit feeding the opposed rectifiers, a source of frequency-variable signal energy coupled to said discriminator, the improvement in the discriminator comprising a signal energy retarding path consisting of a series resonant circuit tuned to the mean frequency of applied signal energy, aperiodic means connecting said series resonant circuit in parallel to said rectifiers, and a pair of non-retarding paths connecting said source to respective rectifiers thereby to apply retarded signal voltage to said rectifiers in opposite polarity, said aperiodic means consisting of a purely resistive connection between the series resonant circuit and each rectifier.

8. In combination with a pair of opposed diode rectifiers having a differential output circuit, a discriminator circuit feeding the opposed rectifiers, a source of frequency-variable signal energy coupled to said discriminator, said discriminator comprising a signal energy retarding path consisting of a series resonant circuit tuned to the mean frequency of applied signal energy, isolating resistors connecting said series resonant circuit in parallel to said rectifiers, a pair of capacity retarding paths connecting said source to respective rectifiers thereby to apply retarded signal voltage to said rectifiers in opposite polarity.

15 9. In combination with a source of frequency modulation signal energy and a pair of opposed diode rectifiers having a differential output circuit, a discriminator circuit comprising a retarding path consisting of a parallel resonant circuit tuned to the mean frequency of applied signal energy, isolation resistor means for applying the output of said parallel resonant circuit in parallel to said rectifiers, a capacitative path feeding the signal energy to one of the rectifiers with a relative phase shift of 90 degrees, a second capacitative path feeding the signal energy to the second rectifier in opposite polarity to the signal energy fed through the first capacitative path but with a similar quadrature phase shift.
